(57) **CLAIM**

The ornamental design for energy storage battery, as shown and described.

DESCRIPTION

1. Energy storage battery

1.1 : Front

1.2 : Back

1.3 : Left

1.4 : Right

1.5 : Top

1.6 : Bottom

1.7 : Perspective

1.8 : Perspective

Use of this product design: This design product is used for energy storage battery, and provide energy for energy storage power supply. Design essentials of this product design: The shape. Picture or image that best illustrates the design essentials: Perspective view 1.7.
